(57) **CLAIM**

The ornamental design for an umbrella pole grip assembly, as shown and described herein.

DESCRIPTION

FIG. 1 is a front view of an umbrella pole grip assembly embodying the new design.

FIG. 2 is a front view of the umbrella pole assembly design shown in FIG. 1.

FIG. 3 is a first side view of the umbrella pole assembly design shown in FIG. 1.

FIG. 4 is a second side view of the umbrella pole assembly design shown in FIG. 1.

FIG. 5 is a rear view of the umbrella pole assembly design shown in FIG. 1.

FIG. 6 is a top view of the umbrella pole assembly design shown in FIG. 1; and,

FIG. 7 is a bottom view of the umbrella pole assembly design shown in FIG. 1.

The broken lines in the drawings depict environmental subject matter that forms no part of the claimed design.

1 Claim, 6 Drawing Sheets
